J. T. GRAY,

TELEPHONE HOOK SWITCH AND CUT-OUT.

APPLICATION FILED MAR. 4, 1916.

1,269,425.

Patented June 11, 1918.

Fig. 1.

UNITED STATES PATENT OFFICE.

JOHN T. GRAY, OF GREAT FALLS, MONTANA.

TELEPHONE HOOK-SWITCH AND CUT-OUT.

1,269,425.

Specification of Letters Patent. Patented June 11, 1918.

Application filed March 4, 1916. Serial No. 82,172.

To all whom it may concern:

Be it known that I, JOHN T. GRAY, a citizen of the United States, residing at Great Falls, in the county of Cascade and State of Montana, have invented certain new and useful Improvements in Telephone Hook-Switches and Cut-Outs, of which the following is a specification.

The present invention relates to telephony and more particularly to new and useful improvements in hook operated switches for use in protecting telephone systems.

An object of my invention is to provide in combination with the usual sub-station circuits a cut-out whereby all of the talking circuits and the generator circuit are completely isolated from the line when the telephone is not in use, whereby to prevent injury of the telephone circuits by lightning or other electrical surges.

Another object of my invention is to provide an improved cut-out of the class described which is combined with the usual hook switch and adapted to be opened when the receiver is on the hook.

A further object of my invention is to provide a modified form of switch for use in connection with a bridging set, whereby to cut in the bell circuit when the talking circuit is open and to cut out the bell circuit when the talking circuit is closed.

A still further object of my invention is to provide in a simple and compact structure a durable switch for coöperation with the hook of the usual telephone set and to provide a switch of this character which opens a sufficient distance to prevent ordinary electrical surges from reaching the talking circuits.

It will be understood that the circuits in which this device is installed do not form any part of my invention and have, therefore, been omitted from the showing.

Other objects and advantages will appear from the following detail description and the claim, taken with an inspection of the accompanying drawings, in which

Figure 1 is a side elevation of my improved cut-out showing the same applied in combination with the usual hook switch,

Fig. 2 is a bottom plan view of the same,

Fig. 3 is a side elevational view of a modified form of the switch.

Referring more particularly to the drawings, wherein similar characters of reference designate like and corresponding parts

throughout the various views, 1 designates a casing in which is mounted the usual telephone set, the usual telephone hook 2 being mounted in the bracket 3 and having the hook portion 4 on the outer end thereof. The usual hook switch is provided, controlled by the hook 2, and comprises the resilient strips 5, 6 and 7 mounted on an insulating support 8. The structure of the hook switch is of the usual kind and need not be further dwelt upon at this time.

My improved cut-out broadly comprises a switch, having a structure hereinafter set forth in detail, interposed in the main leads from the line to the talking circuits and operable to open said circuits when the receiver is on the hook and the latter is in depressed position. As best shown in Figs. 1 and 2 my improved cut-out is designated S in its entirety and comprises conductor arms 9 pivoted at 10 in brackets 11, said brackets being connected to the generator circuit of the phone. Jumpers 12 connected to the arms 9 and brackets 11, respectively, serve to conduct current around the pivots 10 and prevent any electrical disturbances caused by poor contact at these points. The arms 9 are connected to move together by means of a transverse bar 13 of insulating material having a yoke 14 removably secured thereto by means of screws 15, said yoke having an opening therein through which the arm 2 of the receiver hook passes. Thus it will be seen that when the telephone hook is depressed the main switch S comprising the arms 9 will be opened.

Of course the bearing brackets 11 are mounted on a suitable base 16 of porcelain or the like. The leading-in wires from the main line are connected to stationary terminals 17 which are adapted to be engaged by the arms 9, spring strips 18 permanently connected as at 19 to said arms serving to insure true contact. Of course, platinum contacts (not shown) may be employed at the points at which the spring strips 18 engage the terminals 17, but these are modifications that may be made in reducing the device to actual practice.

It will be seen that when the hook 2 is depressed by virtue of the receiver being placed thereon the switch S will be opened, and said switch being interposed in the talking circuits the circuits will be cut out from the main line. It is preferable that considerable distance exist between the switch arms

9 and the terminals 17 when the switch is open in order to insure the talking circuits against injury.

Thus it will be seen that when the receiver is placed upon the hook 2, the arms 9 carrying the spring strips 18 will be caused to move away from the terminal 17 which opens the talking circuit.

Referring to the Fig. 3, an extension 43 is provided in one of the arms 9, said extension having an enlargement 44 on the free end thereof engageable with a spring contact member 45 mounted at 46 on the base 1. The spring contact arm 45 is connected to the bell circuit so that when the talking circuits are open the bell circuit is automatically closed. The sub-station circuits employed in

connection with my improved telephone protector are practically identical with the circuits now in common use.

What I claim as new and desire to secure by Letters-Patent is:—

In a telephone cut-out, the combination with a hook switch, of a main switch including a pair of interconnected pivoted parallel conductor arms, a yoke carried by the arms engaged in said hook switch, spaced rigid contact posts, and spring strips carried by the conductor arms for engaging said contact posts.

In testimony whereof I affix my signature hereto.

JOHN T. GRAY.
